Primary Examiner — Michael A. Pratt(74) *Attorney, Agent, or Firm* — Kim IP Law Group LLC(57) **CLAIM**

The ornamental design for a slide for a firearm, as shown and described.

DESCRIPTION

FIG. 1 is a top perspective view of a slide for a firearm in accordance with the new design;

FIG. 2 is a left-side view of the slide for a firearm of FIG. 1;

FIG. 3 is a right-side view of the slide for a firearm of FIG. 1;

FIG. 4 is a front view of the slide for a firearm of FIG. 1; FIG. 5 is a rear view of the slide for a firearm of FIG. 1; and,

FIG. 6 is a top view of the slide for a firearm of FIG. 1. The broken lines in the figures are directed to portions of a firearm that form no part of the claim. The shaded surfaces in the figures form part of the claim.

1 Claim, 6 Drawing Sheets(56)
